HANDLE EYE CONSTRUCTION OF TOOLS

Ludwig Schwarzmayr, San Francisco, Calif.

Application May 15, 1943, Serial No. 487,412

1 Claim. (Cl. 145—29)

One object of the invention is to provide tools with a handle eye construction which facilitates quick replacement of a broken handle, which is of great advantage when the old handle breaks in the performance of work, which very often happens when pulling big nails with a claw-hammer.

Another object is to more firmly mount the handle in the tool, which is very desirable in striking tools, such as an axe or a hammer.

I attain these objects by the handle eye construction illustrated in the accompanying drawing in which—

Figure 1 is a sectional view of the handle eye construction of the invention in conjunction with a claw-hammer.

Fig. 2 is a sectional view of the handle eye construction of the hammer of Fig. 1 with a handle mounted therein.

Fig. 3 is a section of the handle eye construction of the hammer on line 3—3 in Fig. 1.

Fig. 4 is a sectional view of the handle eye construction of the invention in conjunction with an axe.

Fig. 5 is a sectional view of the improved handle eye construction in conjunction with a sledge-hammer.

Fig. 1 shows a claw-hammer 1, the body 2 of which has a handle eye 3 constructed in accordance with my invention. The walls 4—4 of the intermediate section 5 of the eye 3 are parallel to the longitudinal axis 6 of the eye 3. The handle entrance 7 of the eye has walls 8—8 which are deflected outwardly from the walls 4—4, and on the ends of the deflected walls 8—8 are cutters 9, which, as is shown in Fig. 2, cut surplus wood 10—10 from the handle 11 when the handle is forced into the eye. In the upper end section 12 of the eye the walls 13—13 are slightly deflected outwardly from the walls 4—4. When mounting a handle in the eye of the tool body the leading end 14 is shaped to be received by the handle entrance 7, and when the handle is forced into the constricted section 5 of the eye the deflected walls 8—8 compress the wood of the handle, thereby a greater quantity of wood is caused to enter the eye of the tool than does in handle eyes of common construction, and consequently the handle is mounted more firmly in the body of the tool. To further secure the handle more firmly in the body of the tool

water may be applied to the end portion 14 of the handle and caused to flow into the spaces 15—15 formed between the deflected walls 13—13 and the compressed wood of the handle. When the compressed wood absorbs the water in the spaces 15—15 it expands to its original dimension, whereby a head is formed without the use of a wedge, which is commonly used to form a head to prevent the tool body from sliding from the handle.

Fig. 4 shows the improved handle eye construction in conjunction with an axe, in section. The handle eye 19 in the body 20 of the axe has an intermediate section 21 with walls 22—22 parallel to the longitudinal axis 23 of the eye, and from the walls 22—22 extend the outwardly deflected walls 24—24. The handle entrance section 25 of the eye has walls 26—26 extending from the sides 22—22 in an outwardly deflected position, and on their outer ends are cutters 27, which project from the face 28 of the body of the axe, thereby facilitating the cutting of surplus wood from a handle forced into the eye. The dotted lines 29 show the position of a handle when mounted in the eye of the axe.

Fig. 5 shows the improved handle eye construction in conjunction with a sledge-hammer. The eye 30 in the body 31 of the sledge-hammer has an intermediate section 32 with walls 33—33 parallel to the longitudinal axis 34 of the eye, and the upper end section 36 has walls 37—37 outwardly deflected from the walls 33—33. The handle entrance section 38 of the eye has walls 39—39 outwardly deflected from the walls 33—33, and on the ends of the deflected walls 39—39 are cutters 40, which project beyond the face 41 of the body of the sledge-hammer. The position of a handle when mounted in the eye is shown in dotted lines 42.

40 I claim:

In a handle eye construction of a tool, a tool body having an elongated eye, the walls in the intermediate section of said eye being parallel to the longitudinal axis of the eye, the walls in the handle entrance section of said eye being deflected outwardly from the first mentioned walls, and a cutter on the end of each of said outwardly deflected walls for cutting surplus wood from a handle forced into the eye.

50

LUDWIG SCHWARZMAYR.
